UNITED STATES PATENT OFFICE

2,370,547

AUTOMATICALLY ADJUSTABLE EDGE GUIDE
FOR SEWING MACHINESWalter Kneissler, Roselle, N. J., assignor to The
Singer Manufacturing Company, Elizabeth,
N. J., a corporation of New Jersey

Application December 10, 1943, Serial No. 513,670

9 Claims. (Cl. 112—20)

This invention relates to work-guiding devices for sewing machines and it has as a primary object to provide an edge-guide and means for automatically adjusting the position of the edge-guide relative to the needle in accordance with the thickness of the work. The invention is particularly useful in hosiery seaming machines and it will, therefore, be shown and described in conjunction with that type of machine but it is to be understood that it is not limited thereto.

As shown herein, the invention is embodied in a fabric uncurling and guiding device of the type commonly used on hosiery seaming machines. The device illustrated is an improvement of the device which forms the subject of my United States Patent No. 2,338,043, December 28, 1943.

The blanks of knit material from which full-fashioned stockings are commonly made vary in thickness for different parts of the stockings. For example, the parts which are designed to become the toe and heel portions of the foot and the top or welt portion of the leg, to which the garter is to be attached, are usually made thicker than the portion which is designed to become the leg of the stocking.

Sewing machines customarily used to convert the blanks into completed stockings usually include a horizontally reciprocating needle, a pair of feed-cups presenting the work to the needle in a vertical plane, a device for uncurling the edge of the work, and an edge-guide for so positioning the edge of the work relative to the needle that the needle will pierce the work at a predetermined distance from the edge thereof.

In the interest of strength and appearance, it is desirable that the needle be caused to penetrate the work at a greater distance from the edge thereof and thereby make a heavier seam in the thicker, normally unexposed portions of the stocking than in the thinner leg portion thereof.

This invention therefore has as an object to provide, in an uncurling guide having the usual edge-guide for the work, means actuated by the work and in accordance with the thickness thereof, for shifting the edge-guide vertically relative to the horizontal plane of needle reciprocation, thereby automatically to cause the needle to penetrate the work at a distance from the edge thereof proportionate to the thickness of the work.

Another object of the invention is to provide manually adjustable means for initially positioning the edge-guide at any desired elevation above the plane of reciprocation of the needle, thereby to predetermine the distance from the edge of

the work at which the needle will penetrate the work when sewing the thinner material.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

Fig. 1 is a side elevation of a portion of an uncurling guide embodying the present invention, showing it in its normal position relative to the needle and one of the feed-cups of a stocking seaming machine.

Fig. 2 is a view looking in the direction indicated by the arrow *t* in Fig. 1, showing the uncurling guide in its normal position relative to the needle and to both feed-cups of a stocking seaming machine.

Fig. 3 is an enlarged front view of the lower portion of the improved uncurling guide, showing in full and dotted lines the extreme positions of the uncurling plates and the edge-guide.

Fig. 4 is an enlarged horizontal sectional view taken on the lines 4—4 of Figs. 1 and 2 with a portion thereof broken away.

Fig. 5 is a detail sectional view taken on the line 5—5 of Fig. 3.

Fig. 6 is a side elevation of a portion of a stitched stocking, showing the line of needle penetration at different distances from the edge thereof proportionate to the thickness of the stocking material.

Fig. 7 is a top edge view of the portion of the stocking shown in Fig. 6 showing more clearly the variation in thickness in various parts thereof.

Referring more specifically to the drawing the invention is disclosed as embodied in an uncurling guide which, in Figs. 1 and 2, is shown as applied to a so-called cup-feed sewing machine having a frame, portions of which are designated by the numeral 1, inner and outer rotatable feed-cups 2 and 3, supported by the machine frame, a horizontally reciprocable needle-bar 4 and an eye-pointed needle 5 carried by the needle-bar. Such machines also include a looper mechanism which cooperates with the needle in forming over-edge stitches but inasmuch as that mechanism forms no part of this invention, illustration and description thereof is deemed unnecessary. As shown in Fig. 2, the uncurling guide, which is designated generally as G, also is supported from

the machine frame through the medium of an angle bracket 6.

The uncurling guide comprises a supporting member 7 journaled upon a stud 8 between the bracket 6 and a disk 9 threaded on the outer end of the stud. The member 7 is formed with a depending portion 10, provided with a vertical bore 11, and a horizontally disposed arm 12 in which is secured the upper end of a threaded stud 13. Although the member 7 is pivotally mounted on the stud 8 so that, if desired, the entire uncurler may be swung out of operative position, it is locked in the position shown in Figs. 1 and 2 during the operation of the machine and therefore may be considered to be a fixed supporting member insofar as operation of the device is concerned.

Located beneath the member 7 is a horizontally disposed substantially H-shaped head 14 (see Fig. 4) from which depends a shank 15 of a central fabric-guiding plate 16. Cooperating with the guide-plate 16, in presenting the work to the stitch-forming mechanism, are uncurlers 17 and 18 which are pivotally mounted, intermediate their ends, by pivots 19 and 20, respectively, carried by the head 14. The members 17 and 18 have portions projecting upwardly from their pivot points and have mounted therebetween a coil spring 21 which tends to separate the upper ends of the members, thereby tending to press their lower work-engaging ends 17', 18' toward the plate 16.

Carried by the guide-plate 16 and projecting from opposite sides thereof, is a stud 22, the lower edge 22^a of which serves as a guide for the upper edge of the work. By varying the height of the stud 22 relative to the needle, it is possible to vary the distance from the edge of the work at which the needle will penetrate the work. The members 17 and 18 are provided with clearance apertures 23 for the stud 22.

The head 14 carries a vertically arranged hollow stud 24 (Fig. 1) which is slidably fitted within the bore 11 in the member 7. A coil spring 25 located within the stud 24 has its upper end in contact with the end wall of the bore 11 and bears at its lower end against the bottom wall of the bore in the stud 24. Thus the spring 25 constantly urges the head 14, and the parts carried thereby, downwardly. Downward movement of those parts is limited by a stop-nut 26 threaded upon the shank 26^a of the stop-nut 26 is a collar 27 carrying graduation marks, numbered 1 to 5, adapted to cooperate with a substantially fixed mark *x* later to be referred to. By rotating the nut 26 and the collar 27 any desired predetermined setting of the edge-guide, relative to the needle, may be effected. This setting is usually made in accordance with the thinnest portion of the work to be sewn. A stop nut 30 is adjustably mounted on the stud 13 and serves to limit the movement of the uncurler when it is manually shifted upwardly on its support to prevent "drop-outs" as explained in my above mentioned patent.

As hereinbefore stated, this invention has provided means for automatically varying the position of the edge-guide relative to the needle, whereby the distance from the edge of the work at which the needle will penetrate the work is

proportionate to the thickness of the work. This means will now be described.

Referring to Fig. 4 it will be seen that the pivot 20 on which the uncurler 18 is fulcrumed is a common screw stud having a cylindrical portion 20^a on which the uncurler is journaled and a threaded portion 20^b screwed into the head 14. The pivotal mounting of the uncurler 17 is somewhat different from that of uncurler 18. In the mounting of the uncurler 17 the member 19 is in the form of a pin journaled, at 14^a and 14^b in the head 14. The uncurler 17 is fixedly secured to the pin 19 by a set screw 28. At one end, the pin 19 carries a bifurcated lever-arm 29 which straddles the stud 13 and bears upon the shank 26^a of stop-nut 26, as shown most clearly in Figs. 3, 4 and 5. The outer portion of the lever-arm 29 carries the substantially fixed mark *x*, hereinbefore mentioned, which cooperates with the graduations on the collar 27. The free end of the lever-arm 29 underlies a portion of the head 14 and is maintained in contact with the shank 26^a of the stop-nut 26 by the downward pressure exerted by the spring 25. Inasmuch as the uncurler 17 is fixedly secured to the pin 19 by set screw 28 it follows that outward movement of the lower end 17' of the member 17, that is from the position shown in dotted lines in Fig. 3 to the position shown in full lines, will cause the pin 19 and lever-arm 29 to be turned clockwise about the axis of the pin. Furthermore, as the outer end of arm 29 rests upon the shank of stop-nut 26 on the stationary stud 13 and as the nut cannot be pushed downwardly by the arm, it follows that in such turning movement of the lever-arm it will react upon the pin 19, the head 14 and all parts carried thereby, thus shifting them vertically from the position shown in dotted lines in Fig. 3 to the position shown in full lines. This upward movement of the parts, including the guide-plate 16 lifts the work-engaging lower edge 22^a of the stud 22 from the level indicated by the dotted line *y* in Fig. 3 to the level indicated by the full line *z*, thereby positioning the work-guiding edge 22^a materially further above the line of needle penetration, which is represented by the dot-dash line *n* in Fig. 3.

Figs. 6 and 7 represent a folded stocking blank having relatively thin portions *a*, such, for example, as the leg portion of a stocking and relatively thick portions *b* such as the toe, heel or welt portions.

If this blank is passed through the uncurler with one of the thinner portions *a* on each side of the center guide-plate 16 the needle will penetrate the work along the line *a'* which, it will be seen, is relatively close to the edge *e* of the work. When the thickened portions *b* of the blank pass between the work-engaging ends 17' and 18' of the uncurlers and the center guide-plate, the members 17 and 18 will be forced outwardly about their pivots 19 and 20 and away from the guide-plate 16. This movement of the member 17 rocks the lever-arm 29 which results in the lifting of the edge-guiding stud 22 and, as the edge of the work is kept in contact with the lower edge of this stud, the edge of the work blank also will be raised relative to the horizontal plane of needle reciprocation with the result that the needle will penetrate the thicker work at a greater distance from the edge thereof as indicated by *b'* in Fig. 6.

From the foregoing it will be seen that this invention provides manually adjustable means

for causing the needle to penetrate the work at any desired distance (within certain limits) from the edge thereof and automatic means, controlled by the work, for varying that distance in proportion to variations in thickness of the work.

Having thus set forth the nature of the invention, what I claim herein is:

1. In a sewing machine having a pair of feed cups and a horizontally reciprocating needle, an uncurling guide including a center guide-plate, a work-uncurling member located at each side of said guide-plate and each adapted to bear upon a work-piece passing between said member and said plate, an edge-guide carried by said plate at a predetermined distance above the horizontal plane of reciprocation of said needle, and means automatically brought into effective action by the work-piece for varying the elevation of said edge-guide relative to said needle.

2. In a sewing machine having a pair of feed cups and a horizontally reciprocating needle, an uncurling guide including a center guide-plate, a work-uncurling member located at each side of said guide-plate and each adapted to bear upon a work-piece passing between said member and said plate, an edge-guide carried by said plate at a predetermined distance above the horizontal plane of reciprocation of said needle, manually actuatable means for initially setting said edge-guide at a predetermined elevation above said needle, and means automatically brought into effective action by the work-piece for varying the elevation of said edge-guide relative to said needle.

3. In a sewing machine having a pair of feed cups and a horizontally reciprocating needle, an uncurling guide including a normally fixed supporting member, a center guide-plate and a pair of work-uncurling members mounted on said supporting member for vertical adjustment, an edge-guide carried by said plate, manually adjustable means for initially positioning said guide-plate and work-uncurling members relative to said supporting member thereby to position said edge-guide a predetermined distance above the horizontal plane of reciprocation of said needle, and means actuated by a work-piece in passing between one of said uncurling guides and said guide-plate for varying the elevation of said edge-guide relative to said needle in proportion to the thickness of the work-piece.

4. In a sewing machine having a pair of feed cups and a horizontally reciprocating needle, an uncurling guide including a center guide-plate, a work-uncurling member located at each side of said guide-plate and each adapted to bear upon a work-piece passing between said member and said plate, an edge-guide carried by said plate at a predetermined distance above the horizontal plane of reciprocation of said needle, and means actuated by the work-piece for automatically varying the elevation of said edge-guide relative to said needle in accordance with the varying thickness of the work-piece.

5. In a sewing machine having a work-feeding means and a reciprocating needle, work delivery means including an edge-guide for presenting work to the needle with an edge thereof at a predetermined distance to one side of the line of needle reciprocation, and means actuated by the work for automatically varying the position of said edge-guide relative to the needle in proportion to the thickness of the work.

6. In a sewing machine having a work-feeding

means and a reciprocating needle, work delivery means including a shiftable edge-guide for presenting work to the needle with an edge thereof at a predetermined distance to one side of the line of needle reciprocation, a pair of relatively movable members engaging opposite faces of a work-piece and between which the work-piece moves in its passage to the edge-guide, spring means urging one of said members into pressure contact with the work-piece, and means actuated by said one of said members for shifting said edge-guide, thereby to vary the distance between said edge-guide and needle in proportion to the thickness of the work passing between said members.

7. A fabric uncurling and guiding device for a sewing machine having a reciprocating needle, comprising a supporting member, a guide-plate and a pair of spring-pressed uncurler members carried by said supporting member, each of said uncurler members pressing a work-piece against one side of said guide-plate, an edge-guide carried by said guide-plate for positioning the edge of the work relative to the needle, and means actuated by one of said uncurling members for varying the position of said edge-guide relative to said needle in accordance with the thickness of the work between said one of said uncurler members and said guide-plate.

8. A fabric uncurling and guiding device for a sewing machine having a horizontally reciprocating needle, comprising a supporting member, a head member carried by and vertically movable on said supporting member, a guide-plate and a spring pressed uncurler member carried by said head member, said uncurler member pressing a work-piece against one side of said guide-plate, an edge-guide carried by said guide-plate for positioning the edge of the work relative to the needle, a spring urging said guide-plate and uncurler downwardly, a manually adjustable stop for limiting the downward movement of said guide-plate, edge-guide and uncurler, a pivot-pin by means of which said uncurler is pivotally attached to said head member, a lever-arm carried by said pivot pin and engaging said stop, said lever-arm acting, upon outward movement of said uncurler by an increase in the thickness of work passing between the uncurler and the guide-plate, to lift said uncurler, guide-plate and edge-guide in proportion to the thickness of the work.

9. A fabric uncurling and guiding device for a sewing machine having a reciprocating needle, comprising a supporting member, a stud depending therefrom, a head member carried by said supporting member and vertically movable relative thereto, a normally fixed stop-nut on said stud and underlying said head member to limit the downward movement thereof, a guide-plate and a pair of spring pressed uncurlers carried by said head member, each of said uncurlers pressing a work-piece against one side of said guide-plate, an edge-guide carried by said guide-plate for positioning the edge of the work-pieces relative to the needle, a lever-arm fulcrumed on said head member and having one end engaging said stop-nut, and means actuated by the outward movement of one of said uncurlers for turning said lever about its fulcrum thereby to cause said lever to raise said head member and the parts carried thereby.

WALTER KNEISSLER.
